J. KAUTZKY.

AUTOMATIC SINGLE TRIGGER MECHANISM FOR DOUBLE BARREL GUNS.

APPLICATION FILED APR. 14, 1914.

1,109,632.

Patented Sept. 1, 1914.

UNITED STATES PATENT OFFICE.

JOSEPH KAUTZKY, OF FORT DODGE, IOWA.

AUTOMATIC SINGLE-TRIGGER MECHANISM FOR DOUBLE-BARREL GUNS.

1,109,632.

Specification of Letters Patent.

Patented Sept. 1, 1914.

Application filed April 14, 1914. Serial No. 831,886.

To all whom it may concern:

Be it known that I, JOSEPH KAUTZKY, a citizen of the United States, residing at Fort Dodge, county of Webster, State of Iowa, have invented a new and useful 5 Automatic Single-Trigger Mechanism for Double-Barrel Guns, of which the following is a specification.

My invention consists of novel means for 10 preventing the immediate discharge of the second barrel after the discharge of the first barrel.

It further consists of novel means for actuating the trigger by the movement of 15 the safety block, in order to insure the engagement of a portion of the trigger with said block.

It further consists of means for returning 20 the block to unlocking position by movement of the trigger.

It further consists of other novel features of construction, all as will be hereinafter fully set forth.

For the purpose of illustrating my invention, I have shown in the accompanying drawings one form thereof which is at present preferred by me, since the same will give in practice satisfactory and reliable results, although it is to be understood that 25 the various instrumentalities of which my invention consists can be variously arranged and organized, and that my invention is not limited to the precise arrangement and organization of these instrumentalities as 30 herein shown and described.

Figure 1 represents a side elevation of the frame of a breech loading double-barrel gun, in detached position, and showing my invention carried thereby. Fig. 2 represents 40 a sectional view on line α — α Fig. 1. Fig. 3 represents a longitudinal vertical section of portions of the device, on line y — y Fig. 2, in cocked position. Fig. 4 represents a longitudinal vertical section, showing portions 45 of the device on line z — z Fig. 2, in fired position. Fig. 5 represents a vertical sectional view of certain of the parts seen in Fig. 1, showing the same in fired position, showing the block 22 wedged between the 50 abutment 20 and the shoulder 21. Fig. 6 represents a vertical sectional view on line a — a , Fig. 1. Fig. 7 represents, in detached position, an elevation of the selective lever, and parts operable therewith. Fig. 8 represents 55 a side elevation of portions of the device seen in Fig. 7, in a different position.

Similar numerals of reference indicate corresponding parts in the figures.

Referring to the drawings: 1 designates a frame for a gun lock, comprising the tang 60 2 and the trigger plate 3, said frame being provided with means adapted for supporting two barrels (not shown) at its front end portion.

4 designates hammers, which are pivotally mounted in the frame 1 in a suitable manner, and which are acted upon in any suitable or desired manner for moving the same to fired position, when released, each of said hammers having a sear notch 5 at a 70 suitable point thereon.

6 and 7 designate the sears pivotally mounted with respect to the frame and said hammers, each being provided with a sear nose 8 adapted for engagement with the 75 sear notch 5 of a hammer. Suitable springs 9 act upon said sears, tending to depress the same. Adjacent the end of each sear, opposite to that of the nose 8, is a lug or arm 10 and 11 respectively, each lug being provided 80 with a flat, inclined, lower face 12.

13 designates a tumbler pivotally mounted, in the present instance, on the trigger-plate, at a suitable point with respect to the lug ends of the sears, the upper face of said 85 tumbler being provided with the oppositely inclined faces 14 and 15, adapted and properly located for engagement with the faces 12 of the lugs 10 and 11, and a roller 16 is journaled to the free lower end of the said 90 tumbler 13.

17 designates a trigger pivotally mounted in any suitable or desired manner in the frame 1, and which, as here shown, is provided with a cam 18, which is adapted to 95 engage with and be engaged by the said roller 16, by means of which contact, the tumbler 13 is turned into engagement with the lugs 10 or 11, respectively, of the sears, when the trigger is pulled, as will be hereinafter described. The trigger 17 carries an upwardly projecting member 19, here shown as integral therewith, and on said member I provide an abutment or lug 20, which projects laterally sufficiently from the member 100 19 for the purpose hereinafter described.

21 designates a projection or shoulder carried by the said trigger.

22 designates the safety block, which is pivotally mounted in any suitable manner 110 in operative relation to said trigger, at a point slightly to the rear and laterally of

said member 19, said block having a portion thereof suitably located and adapted for engagement with the projection or shoulder 21 of the trigger, this portion being shown, as a laterally extending lug 23, having a face adapted to engage said shoulder 21 at the proper time.

24. designates a spring adapted to bear suitably upon a portion of said block, in order to provide a yielding bearing thereagainst, so that while permitting movement of said block, the said spring serves to hold said block in either locking or unlocking position after said block has been actuated.

15. The inoperative or unlocking position of said block 22 is seen in Figs. 2 and 3, out of the path of, and out of engagement with, the abutment 20 of the member 19. In the present instance, I have shown the spring 20 formed with two bearing members engaging the curved upper faces 25 and 26 on said block, but any suitable means may be employed for accomplishing the desired action. I preferably form the upper face of the 25 block curved, as at 27, for ease of operation of the parts.

In order to provide for which barrel,—that is, the right or left—shall be discharged first, I have mounted a selector attachment, 30 consisting of a slide 28 movably mounted in the frame 1 and provided with a spring 29, extending rearwardly therefrom, and which is provided with an end which is preferably V-shaped, as at 30, and adapted 35 for engagement with the underside of the tumbler 13, said slide 28 being adapted to be positioned by the operator, in order that the said end 30 of the spring 29 will engage the said tumbler 13 on one side or the 40 other of the pivotal point 31 thereof. As seen in Fig. 7, the said end 30 is in engagement on the underside of the tumbler 13, in front of the pivotal point 31, in order that the upper face 14 of said tumbler is in 45 position to engage with the lug 10 of the sear 6. When the slide 28 is moved to its opposite position, that is, in the direction indicated by the arrow in Fig. 7, the end 30 of the spring 29 is moved to the other side 50 of the pivotal point 31 of the tumbler 13, causing it to assume the position seen in Fig. 8, with its other face 15 in position to engage with the lug 11 of the other sear 7. At the same time, by this movement, the roller 16, 55 carried by the tumbler 13, will be properly positioned with respect to the cam 18 of the trigger 17, in order to properly actuate the tumbler 13 to actuate the lug in engagement therewith.

60. The operation of the device will be readily understood. By opening the gun for loading, and returning the barrels to their proper position, the hammers 4 will be properly cocked; that is, they will be in the position seen in Fig. 1, with the sear noses 8 in

engagement with the respective notches 5 of the hammers 4. The slide 28 may now be moved to position the tumbler 13, depending upon which barrel it is desired to fire first. Considering that the same is in the position seen in Fig. 1, the parts will be in position to fire the right-hand barrel first, with the roller 16 on the left-hand side of the cam 18 of the trigger 17. By a rearward pull upon the trigger 17, it will be understood that the roller will be elevated, rotating the tumbler, upon its pivotal point 31, and elevating the lug 10 in engagement therewith, thus raising the end of the sear 6, releasing the hammer from engagement with the sear, and firing the right hand barrel. As the trigger moves rearwardly and the gun is fired, the force of the recoil will overcome the bearing of the spring 24 on the block 23, and will rotate the block 22 upon its pivotal point, 70 and position the upper surface 27 thereof beneath the abutment 20 on the member 19 of the trigger 17, and when pressure on the trigger is suddenly released by the recoil, the abutment 20 engages the said upper face 75 of the block 22, see Fig. 5, said block being wedged between the abutment 20 and the shoulder 21. This engagement is only temporary, as the rebound of the gun from the shoulder of the operator will cause the trigger to engage his finger and be slightly raised, which will elevate the abutment 20, and the block 22 will be released from engagement therewith, and the shoulder 21 on 80 the trigger in engagement with the lug 23 will overcome the holding action of the spring 24 and will rotate said block 22 on its pivotal point and it will return to normal or unlocking position ready for the next firing. In order to fire the second barrel, 85 therefore, it is necessary for the operator to release the trigger, allowing the same to move downwardly, and the end of the right sear 6, which has been previously raised, is 90 lowered by the action of the spring 9, 100 with suitable force, to cause the lug 10 to strike the face 14 of the tumbler 13 and rotate the same on its pivotal point, thus moving it from its position in Fig. 1, to that 105 seen in Fig. 3, causing the roller 16 to be 110 moved to the opposite side of the cam 18, with its face 15 in engagement with the other lug 11 of the other sear 7, so that by a second rearward pull of the trigger, the left 115 barrel will be discharged in the same manner as the first.

It will thus be seen from the above, that I have provided a safety device, which is mounted upon the frame independently of the trigger and normally out of engagement 120 therewith, but which is adapted to be actuated by the recoil to be moved in the path of, and to engage with, a suitable portion of the trigger to prevent the involuntary or premature firing of the second barrel, after 130

the first barrel has been discharged, and this action is assisted by the movement of the block, while the trigger, when moved by the rebound, rotates the block to unlocking position.

5 It will now be apparent that I have devised a novel and useful construction of an automatic single-trigger mechanism for double-barrel guns, which embodies the features 10 of advantage enumerated as desirable in the statement of the invention and the above description, and while I have in the present instance, shown and described a preferred embodiment thereof which will give in practice satisfactory and reliable results, it is to 15 be understood that the same is susceptible of modification in various particulars without departing from the spirit or scope of the invention or sacrificing any of its advantages.

20 Having thus described my invention, what I claim as new and desire to secure by Letters Patent is:—

1. In a device of the character stated, a plurality of firing means, a trigger provided 25 with means for successively actuating said firing means, a laterally extending shoulder carried by a member of said trigger, and a block mounted in operative relation to said member and laterally thereof and normally 30 out of engagement with said shoulder, and arranged to be moved by the recoil to a position with its face beneath said shoulder to be temporarily engaged thereby in this one position of said block to prevent said trigger 35 from being released involuntarily by the recoil.

2. In a device of the character stated, a plurality of firing means, a trigger provided with means for successively actuating said 40 firing means, a laterally extending shoulder carried by a member of said trigger, and a block, having a curved face, mounted in operative relation to said member and laterally thereof and normally out of engagement 45 with said shoulder, and arranged to be moved by the recoil to a position with its upper face beneath said shoulder to be temporarily engaged thereby in this one position of said block to prevent said trigger 50 from being released involuntarily by the recoil.

3. In a device of the character stated, a plurality of firing means, a trigger provided with means for successively actuating said 55 firing means, a laterally extending shoulder carried by said trigger, a block mounted in operative relation to said shoulder, and adapted to be moved to a position with its upper face beneath said shoulder to be engaged thereby to prevent said trigger from 60 being released involuntarily by the recoil, and means on said trigger for moving said block to unlocking position.

4. In a device of the character stated, a 65 plurality of firing means, a trigger pro-

vided with means for successively actuating said firing means, a laterally extending shoulder carried by said trigger, a block mounted in operative relation to said shoulder, and adapted to be moved to a position with its upper face beneath said shoulder to be engaged thereby to prevent said trigger from being released involuntarily by the recoil, means on said trigger for moving said block to unlocking position, and yielding 70 means for holding the block in either locking or unlocking position.

5. In a fire arm, the combination with a plurality of firing means, of a trigger provided with means for successively actuating 80 the firing means and having a locking abutment, a detent mounted in operative relation to said abutment and adapted to be moved to engage therewith upon the discharge of said gun, and means on said detent adapted to engage said trigger during 85 the movement of said detent to actuate said abutment to engage said detent.

6. In a fire arm, the combination with a plurality of firing means, of a trigger provided with means for successively actuating 90 the firing means and having a locking abutment, a detent mounted in operative relation to said abutment and adapted to be moved to engage therewith upon the discharge of said gun, means on said detent adapted to engage said trigger during the movement of said detent to actuate said abutment to engage said detent, and means carried by said trigger for positively moving 95 said detent out of engagement with said abutment.

7. In a fire arm, the combination with a plurality of firing means, a trigger provided with means for successively actuating the 105 firing means and having a locking abutment, a detent mounted in operative relation to said abutment and adapted to be moved to engage therewith upon the discharge of said gun, means on said detent adapted to engage said trigger during the movement of said detent to actuate said abutment to engage said detent, means carried by said trigger for positively moving said detent out of engagement with said abutment, and yielding 110 means engaging said detent for holding the same in either operative or inoperative positions.

8. In a fire arm, the combination with a plurality of firing means, of a trigger provided with means for successively actuating the 120 firing means and having a locking abutment, a detent mounted in operative relation to said abutment and adapted to be moved to engage therewith upon the discharge of said gun, and a lug on said detent adapted to be engaged by said trigger for moving said detent out of engagement with said abutment.

9. In a fire arm, the combination with a 130

plurality of firing means, of a trigger provided with means for successively actuating the firing means and having a locking abutment, a detent mounted in operative relation to said abutment and adapted to be moved to engage therewith upon the discharge of said gun, and means on said detent adapted to be engaged by said trigger for moving said detent out of engagement with said abutment.

10. In a fire arm, the combination with a plurality of firing means, of a trigger provided with means for successively actuating

the firing means and having a locking abutment, a detent mounted in operative relation to said abutment and adapted to be moved to engage therewith upon the discharge of said gun, and means common to said trigger and said detent for moving the latter out of engagement with said abutment.

JOSEPH KAUTZKY.
